UNITED STATES PATENT OFFICE.

JOSEPH P. BARNES, OF ROCKFORD, ILLINOIS, ASSIGNOR TO W. F. & JOHN BARNES COMPANY, OF ROCKFORD, ILLINOIS, A CORPORATION OF ILLINOIS.

FIRE-ARCH FOR FURNACES.

No. 826,645.

Specification of Letters Patent.

Patented July 24, 1906.

Application filed May 17, 1905. Serial No. 260,885.

To all whom it may concern:

Be it known that I, JOSEPH P. BARNES, a citizen of the United States, residing at Rockford, in the county of Winnebago and State 5 of Illinois, have invented certain new and useful Improvements in Fire-Arches for Furnaces, of which the following is a specification.

The object of this invention is to construct 10 a fire-arch for furnaces in which each individual brick can be removed without removing the others.

In the accompanying drawings, Figure 1 is 15 a partial plan view of the fire-arch. Fig. 2 is a vertical section on dotted line *a a*, Fig. 4. Fig. 3 is a vertical section on dotted line *b b*, Fig. 4. Fig. 4 is a lengthwise-vertical section. Fig. 5 is an isometrical representation 20 of one end of one of the supporting-bars. Fig. 6 is an isometrical representation of one end of the supporting-bar. Fig. 7 is an isometrical representation of one of the bricks.

The masonry composes the sides, leaving a fire-chamber between them. The masonry 25 supports a cross-bar 1 by its ends 2. This cross-bar has a hook edge 3. The masonry supports a series of cross-bars 4 by their ends 5. Each cross-bar has a hook edge 6. A cross-bar 7 has its ends 8 supported by the 30 masonry and is provided with a hook edge 9. From one face of this cross-bar extends a ledge 10, having its free edge upturned. Braces 11 connect the ledge with the main portion of the cross-bar.

At Fig. 7 is shown one of the bricks 12, in 35 one face of which is formed a hook 13. A hook 14 is provided with the two curved ends 15 and 16. Each of the bricks 17 is suspended by a hook 14, and each hook is 40 suspended by a link 18, one end of which engages the curved end of the hook and the other end engaging the hooked edge 3 of the cross-bar 7. The bricks 12 are each suspended by hooks engaging the hooked edge 45 of the cross-bars 4. The bricks 19 are suspended by the hooked ledge 10 of the cross-

bar 7. These bricks when suspended, as shown at Fig. 4, form the fire-arch of a furnace.

If any one brick becomes broken, it can be 50 removed and replaced without removing any of the others.

I claim as my invention—

1. A fire-arch for furnaces comprising a series of beams having their lower edges in single hook form, a series of double-ended hooked links having their hooks facing in the same direction and suspended by one of the hooks in engagement with the hooked lower edges of the beams, a series of fire-bricks 60 each having a recessed face in hook form which receive the lower hooked ends of the links. 55

2. A fire-arch for furnaces comprising a series of beams having their lower edges in single hook form, one of the beams having a hooked ledge located above its lower end, a series of double-ended hooked links having their hooks facing in the same direction and suspended by one of the hooks in engagement with the hooked lower edges of the beams, a series of fire-bricks each having a recessed face in hook form, which receives the lower hooked ends of the links, and another series of fire-bricks each having a recessed face in hook form and suspended by the elevated hooked ledge of one of the beams. 65 70

3. A fire-arch for furnaces comprising a beam having a lower edge in single hook form, a series of double-ended hooked links having 80 their hooks facing in the same direction, a series of supplemental double-ended hooked links suspended from the hooked lower edge of the beam and from which the first-named hooks are suspended, and a series of fire-bricks each having a recessed face in hook form which receives the lower ends of the first-named hooks. 85

JOSEPH P. BARNES.
